Primary Examiner — Michelle E. Wilson*Assistant Examiner* — Clese Moore, Jr.(74) *Attorney, Agent, or Firm* — Wood Herron & Evans LLP**CLAIM**

The ornamental design for a ladder for a vehicle, as shown and described.

DESCRIPTION

FIG. 1 is a front top left perspective view of a ladder for a vehicle according to the present invention.

FIG. 2 is a front left perspective view of the ladder shown in FIG. 1.

FIG. 3 is a rear top right top perspective view thereof.

FIG. 4 is a rear right top perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.
